United States Patent Office

Des. 187,941
Patented May 17, 1960

187,941

HOLDER FOR CULINARY IMPLEMENTS AND THE LIKE

Richard S. Latham, Chicago, Ill., assignor to Ekco Products Company, Chicago, Ill., a corporation of Illinois

Application February 19, 1959, Serial No. 54,676

Term of patent 14 years

(Cl. D44—29)

Fig. 1 is a top plan view of a holder for culinary implements and the like, showing my new design.

Fig. 2 is a side elevational view thereof.

Fig. 3 is an enlarged fragmentary section along line III—III of Fig. 1.

I claim:

The ornamental design for a holder for culinary implements and the like, as shown.
